UNITED STATES PATENT OFFICE.

ALBERT PATITZ, OF MERIDEN, CONNECTICUT, ASSIGNOR TO THE BRADLEY & HUBBARD MFG. CO., OF SAME PLACE.

DESIGN FOR A LAMP-FOUNT HOLDER.

SPECIFICATION forming part of Design No. 25,875, dated August 4, 1896.

Application filed July 2, 1896. Serial No. 597,914. Term of patent 3½ years.

To all whom it may concern:

Be it known that I, ALBERT PATITZ, of Meriden, in the county of New Haven and State of Connecticut, have invented a new Design for a Lamp-Fount Holder; and I do hereby declare the following, when taken in connection with the accompanying drawing and the letters of reference marked thereon, to be a full, clear, and exact description of the same, and which 10 said drawing constitutes part of this specification and represents a perspective view of a lamp-fount holder embodying my design.

This invention relates to a design for a lamp-fount holder; and the design consists 15 in the configuration and ornamentation as shown in the accompanying illustration and hereinafter described.

As herein shown, the holder is of bowl-shape and consists of a series of open ornate 20 foliated sections A, connected by upwardly-springing conventionalized acanthus leaves

B, represented as springing from a beaded band C, from which depends an open-work base D, contracting at its lower portion, as at E. The upper edge of the holder is 25 surrounded by a plain band F, from which springs an upwardly-curving and outwardly-flaring open leaf-and-scroll ornamentation G, forming the upper finish of the lamp-fount holder, all as shown in the accompanying illustration. 30

I claim—

The design for a lamp-fount holder as herein described and shown in the accompanying illustration.

In testimony whereof I have signed this 35 specification in the presence of two subscribing witnesses.

ALBERT PATITZ.
